Primary Examiner—Catherine E. Kemper

[57] CLAIM

The ornamental design for a heater for attachment to clothes dryer exhaust, substantially as shown and described.

DESCRIPTION

FIG. 1 is a perspective view of a heater for attachment to clothes dryer exhaust, showing my new design and shown with the front screen opened;

FIG. 2 is a front elevational view thereof with the front screen closed;

FIG. 3 is a left side elevational view thereof;

FIG. 4 is a rear perspective view thereof.

The broken line disclosure of a portion of a clothes dryer exhaust pipe in FIG. 3 is for illustrative purposes only and forms no part of the claimed design. The screen and filter elements are shown partially broken away in FIG. 1 for ease of illustration and a complete disclosure.

FIG.1

FIG.2

FIG.3

FIG.4
